Patented Nov. 28, 1916.

UNITED STATES PATENT OFFICE.

AUGUST FRYKMAN, OF SOURIS, NORTH DAKOTA.

PISTON-RING.

1,206,691.

Specification of Letters Patent. Patented Nov. 28, 1916.

Application filed July 21, 1916. Serial No. 110,533.

To all whom it may concern:

Be it known that I, AUGUST FRYKMAN, a citizen of the United States, residing at Souris, in the county of Bottineau, State of North Dakota, have invented a new and useful Piston-Ring; and I do hereby declare the following to be a full, clear, and exact description of the invention, such as will enable others skilled in the art to which it appertains to make and use the same.

This invention relates to an improved expansible piston ring, particularly adapted for use in connection with pistons and the like and at the ends of cylinders, to prevent leakage of steam or other expansive fluids.

An object of the invention is the provision of a piston ring having separable ends, which are considerably less in thickness than a diametrically opposite portion of said ring. In other words, the wall of the ring tapers in thickness in opposite directions from a point diametrically opposite said separable ends, to said separable ends, thereby affording means to cause the ring 25 to expand against the cylindrical wall of the cylinder.

A further object of the invention is to provide the separable ends with sidewise overlapping parts and an inner cover plate underlying said sidewise overlapping parts, thereby affording a joint, which is steam or fluid escape proof.

A further object of the invention is to provide means upon one face of the cover plate engaging correspondingly shaped means upon the inner face of one of said separable ends, to force the sidewise overlapping parts closely together.

In practical fields, the details of construction may necessitate alterations falling within the scope of what is claimed.

The invention comprises further features and combination of parts, as hereinafter set forth, shown in the drawings and claimed.

In the drawings: Figure 1 is a view in perspective of the improved piston ring constructed in accordance with the invention. Fig. 2 is an enlarged detail perspective view of a portion of the ring, showing the separable ends separated. Fig. 3 is a perspective view of a piston ring, showing a modified structure for more closely connecting the separable ends. Fig. 4 is an enlarged detail perspective view of the separable ends joined, showing the structure illustrated in Fig. 3. Fig. 5 shows the separable ends that

are shown in Fig. 4 separated. Fig. 6 is a sectional view on line 6—6 of Fig. 4.

Referring more especially to the drawings, 1 designates the piston ring which is provided with separable end portions 2 and 3. The ring at a point diametrically opposite the end portions 2 and 3 is thicker than said end portions. In other words, from the point *a* the ring tapers in thickness in opposite directions, as indicated by the arrows *b* and *c* toward and to the separable end portions 2 and 3. One side of the end portion 2 is provided with a recess or cut away portion 4, while the diagonally opposite side of the end portion 3 is provided with a similar recess or cut away portion 5, which diagonal opposite recesses or cut away portions 4 and 5 receive the diagonal oppositely disposed tongues 6 and 7, which are caused to be formed by constructing the recesses 4 and 5. It is to be noted that the adjacent faces of said tongues so frictionally engage as to assist in preventing leakage of steam or the like. The inner face of the end portion 2 has formed integrally therewith an extension cover plate 8, which is of sufficient length to underlap the sidewise overlapping tongues 6 and 7 and the recesses 4 and 5, to further assist in preventing leakage of the steam or the like. In Figs. 3, 4, 5 and 6, the inner face of the end portion 3 adjacent the recess 5 is provided with a groove 9 V-shaped in cross section, which is disposed at a slight angle to the side edge of the piston ring. This angle or inclination is so infinitesimally slight as to be hardly perceptible, and the groove is designed to receive a correspondingly disposed rib 10, V-shaped in cross section, on the outer face of the underlapping cover plate, whereby as the diagonally opposite tongues 6 and 7 enter their respective diagonally opposite recesses 4 and 5, the adjacent faces of said tongues 6 and 7 will so frictionally and movably contact as to insure against any possible leakage of steam or other fluid, when the piston ring is in use on a piston or adjacent the head of a cylinder.

The invention having been set forth, what is claimed as new and useful is:

An expansible piston ring having separable free ends, said separable ends having diagonally opposite recesses adjacent their sides, and provided with diagonally opposite side tongues to enter said diagonally opposite recesses, whereby the tongues will

sidewise overlap each other, one of said ends having integral therewith on its inner face a cover plate of sufficient length to entirely overlap said diagonally opposite recesses and 5 tongues to insure against leakage, the inner face of one of said ends adjacent its respective recess having a groove at a slight incline to the side edge of the ring, the outer face of said cover plate having a rib correspondingly inclined and designed to enter 10

said groove, to force the adjacent faces of the sidewise overlapping tongues, to so frictionally engage as to insure against leakage.

In testimony whereof I have signed my name to this specification in the presence of 15 two subscribing witnesses.

AUGUST FRYKMAN.

Witnesses:

LAWRENCE SCHUR,
V. F. PRYKENSEN.
